UNITED STATES PATENT OFFICE.

FRANK DITCHFIELD, OF MONTREAL, QUEBEC, CANADA.

DUMP-CAR-OPERATING MECHANISM.

1,189,353.

Specification of Letters Patent.

Patented July 4, 1916.

Application filed September 20, 1915. Serial No. 51,634.

To all whom it may concern:

Be it known that I, FRANK DITCHFIELD, a citizen of the Dominion of Canada, and resident of the city of Montreal, in the Province of Quebec and Dominion of Canada, have invented certain new and useful Improvements in Dump - Car - Operating Mechanism, of which the following is a full, clear, and exact description.

This invention relates to improvements in operating mechanism for railway dump cars, and the object of the invention is to provide mechanism particularly adapted to cars having swing-out side doors and swing-down floor doors, such as described in detail in my copending application, Ser. No. 51,633 filed September 20, 1915.

A further object is to provide an operating mechanism for cars of this type arranged to connect the side and floor doors, whereby the doors operate simultaneously and assist one another in both opening and closing.

The device consists essentially of a lever fixed to the side door at its axis of suspension and connected at its free end with the floor door by means of a link. An operating shaft is provided extending from end to end of the car, so that the doors may be operated simultaneously at both ends without subjecting the doors to torsional stress. This shaft is provided with cranks connected at their free ends with the side doors by means of links, so that on the operation of the shaft, the side door will be moved and will through its connection with the floor door move the latter.

In the drawings which illustrate the invention:—Figure 1 is a partial end view of a car showing the operating mechanism and doors in both open and closed positions. Fig. 2 is a plan view of the mechanism at one end of a car. Fig. 3 is a fragmentary side elevation showing one method of connecting the mechanism with the side door at its axis of suspension. Fig. 4 is a fragmentary longitudinal section of the floor door showing the method of connecting the operating mechanism thereto. Fig. 5 is an end elevation of one of the combined floor door hinges and operating shaft bearings.

Referring more particularly to the drawings, 11 designates the center sill of a car, and 12 the body ends fixed thereto, between which the side doors 13 are suspended by means of trunnions 14 located at their up-

per corners. The floor doors 15 are hinged to the center sill at their inner edges, and are provided at their outer edges with tracks 16 for the engagement of rollers 17 mounted on the lower edge of the side door. Brackets 18 are secured to the center sill at suitable intervals, and are provided with hollow cylindrical portions 19 in which the operating shaft 20 is revolvably mounted. Brackets 21 are secured to the side doors and are revolvably mounted upon the cylindrical portions 19.

Any suitable operating mechanism of known design is provided for the operating shaft, of which only the ratchet wheel 22 is shown. The end of the shaft is provided with a crank 23 preferably formed in two webs, between which a link 24 is pivotally mounted at one end, as shown at 25. The opposite end of the link is pivotally mounted on a pin 26 secured to the lower edge of the side door. This link is bent intermediate its ends at 27, so that the shaft may be rotated sufficiently to bring the pivotal point 25 across a produced line drawn through the pivotal point 26 and the center of the shaft 20, before the link strikes the shaft 20.

A lever 28 is fixed at one end to the trunnion 14 and is pivotally connected at its free end with one end of a link 29. The opposite end of the link 29 is pivotally mounted on a pin 30 secured to the end of the floor door intermediate its inner and outer edges.

It will be seen that the cranks 23 overlap at the center of the car, thus bringing one link 24 farther from the end of the car than the other. In order to avoid a multiplicity of different parts in the manufacture of the car, it has been found advisable to make both the cranks and the links with the hubs thereof projecting from one side, so that by turning the hub in on one member and out on the other member, the desired clearance will be obtained, and the shafts and pivot pins 26 will also be duplicates. The dimensions of the parts and the positioning of the pivot points are not relatively fixed, but must be determined according to the weight, size and angle of the doors in both open and closed positions, so that the only rule which can be laid down on this point is that the dimensions of the parts and the positioning of the pivotal points must be such that the weight of the load pressing down on the floor door

will suffice, when the doors are unlocked, to raise the side door out of the path of the escaping load, and when the car is empty, to permit the side door, in falling to closed position by the action of gravity, to raise the floor door to closed position against the action of gravity.

The operation of the device is extremely simple and will be readily understood from the drawings and foregoing description, and may be summarized as follows:—When the car is closed and locked, the parts are in the position shown in full lines, Fig. 1. To unlock the car, the shaft 20 is rotated through an angle of a few degrees to the right, forcing the lower edge of the side door out of engagement with the outer edge of the floor door. The floor door naturally presses down on the side door and would render this unlocking difficult, if it were not for the mechanism comprising the lever 28 and link 29, by means of which the downward pressure of the floor door also operates to throw the side door outwardly. When once the doors have disengaged, the weight of the load on the floor door depresses the same to its limit of movement, and at the same time through the medium of the link 29 and lever 28, raises the side door to full open position out of the path of the escaping load, as shown in broken lines, Fig. 1. When the load has been discharged, the downward pressure on the floor door is removed, and all that retains the floor door open is the pull of gravity, which may be expressed as one-half the weight of the door, the other half being supported by the center sill.* The side door being supported at its highest point, the action of gravity is to close the same, and as the nature of the car to which this mechanism is applicable usually requires a much heavier side door than floor door, the greater weight of the side door, combined with the leverage which it exerts, owing to its position, enables it to raise the floor door through the medium of the lever 28 and link 29. At the same time, the inwardly moving lower edge of the side door operates through the link 24 and crank 23 to rotate the shaft 20 toward the left. If the momentum of the doors is not sufficient to entirely close the same, the doors will come to a state of equilibrium very near the closed position, and rotation of the shaft 20 will operate through the crank 23 and link 24 to draw the side door into fully closed position, and at the same time raise the floor door to fully closed position through the medium of the side door, the lever 28 and the link 29. It is obvious that since such an operation will commence from a point where the doors are in equilibrium, there will at the outset be no appreciable resistance to the movement, and before the resistance develops to a degree nearly equaling the strength of the operator, the side door

will be drawn under the floor door and the roller 17 will have a camming action on the track 16, sufficient to raise the floor door to fully closed position, without increase of effort and entirely irrespective of the parts 28 and 29. The shaft is then rotated to bring the crank 23 and link 24 to the position shown in full lines, with the point 25 below the projected line through the centers of the pins 26 and shaft 20, so that when the car is again loaded, outward thrust of the load on the side door will tend to produce continued revolution of the shaft in the closing direction, which is, however, checked by the engagement of the link on the shaft 20, so that the mechanism locks itself without the use of additional parts.

Having thus described my invention, what I claim is:—

1. In a car, the combination with a side door and a floor door, of a lever rigidly connected to the side door, and a link connecting the free extremity of said lever with the floor door.

2. In a car, the combination with a side door pivotally supported at its upper edge and a floor door pivotally supported at its inner edge, of a lever fixed to said side door at the pivotal axis thereof, and a link connecting said lever with a point on the floor door intermediate the inner and outer edges thereof.

3. In a car, the combination with a side door pivoted at its upper edge and a floor door pivoted at its inner edge, of a lever rigidly connected to each end of the door at the pivotal axis thereof, a link extending from each lever to the floor door and pivotally connected to the door at a point intermediate the inner and outer edges thereof, the length of said levers being approximately equal to the distance between the pivotal axis of the floor door and the pivotal connection of the links with said floor door.

4. In a car, the combination with a pivotally suspended side door of a floor door pivotally supported at one edge and supported at the opposite edge by said side door, an operating shaft, a crank thereon, and a link connecting said crank and the side door arranged to draw the same into engagement with the floor door.

5. In a car, the combination with a side door pivotally suspended at the upper edge and a floor door pivotally suspended at one edge and supported at the opposite edge by the side door, of an operating shaft, a crank thereon, a link connecting the crank and side door and arranged to draw the side door into engagement with the floor door and lock the same.

6. In a car, the combination with a side door pivotally suspended at the upper edge and a floor door pivotally suspended at one edge and supported at the opposite edge by

the side door, of an operating shaft, a crank thereon, and a link connecting the crank and side door and arranged to draw the side door into engagement with the floor door 5 and lock the same, said link being offset whereby motion of the crank will be checked by engagement of the link and shaft after the crank has passed over the line including the centers of the shaft and 10 point of connection between the link and door.

7. In a car, a floor door pivotally supported at its inner edge, a side door pivotally supported at its upper edge and at its 15 lower edge supporting the outer edge of the floor door, an operating shaft, a crank thereon, link connection between said crank and the side door, a lever fixed to the side door at its pivotal axis, and a link connecting 20 said lever and the floor door.

8. In a car, a side door pivotally suspended at its upper edge, a floor door pivotally supported at its inner edge and at its outer edge supported by the side door, 25 tracks at the outer edge of said floor door, and rollers at the lower edge of said side door positioned to travel on said tracks.

9. In a car, a side door pivotally suspended at its upper edge, a floor door pivotally supported at its inner edge and at its outer edge supported by the side door, 30 tracks at the outer edge of said floor door, and rollers at the lower edge of said side door positioned to travel on said tracks, connection 35 between said side and floor doors arranged to raise the floor door on inward movement of the side door, an operating shaft, and connection between the operating shaft and side door arranged to draw the 40 same inwardly to a position of engagement under the floor door.

10. In a car, the combination with a side door pivotally supported at its upper edge and a floor door pivotally supported at its 45 inner edge, of a shaft, and means operated by the shaft for simultaneously raising the floor door and drawing the side door into engagement under the floor door, said floor door raising means including the side door 50 and its operating means.

11. In a car, the combination with a side door pivotally supported at its upper edge and normally closable by the action of gravity, and a floor door pivotally support-

ed at one edge and normally openable by 55 the force of gravity, of connection between the side and floor doors, whereby closing of the side door simultaneously closes the floor door.

12. In a car, the combination with a side 60 door pivotally supported at its upper edge and normally closable by the action of gravity, and a floor door pivotally supported at one edge and normally openable by the force of gravity, of connection between 65 the side and floor doors, whereby closing of the side door simultaneously closes the floor door, an operating shaft, and means connecting the operating shaft and side door arranged to lock the side door against open- 70 ing movement.

13. In a car, the combination with a side door pivoted at its upper edge and a floor door pivoted at its inner edge and adapted at its outer edge for engagement with the 75 side door, of means connecting the side and floor doors whereby closing movement of the side door due to the action of gravity will produce simultaneous closing movement of the floor door against the action of gravity 80 and bring the doors into equilibrium in partially closed position, a revoluble locking shaft, and means connecting the shaft and side door arranged to draw the side door to fully closed position in engagement under 85 the floor door, and simultaneously raise the floor door to fully closed position through the medium of the side door and its connection with the floor door.

14. In a car, the combination with side 90 and floor doors, and an operating shaft, of a toggle mechanism arranged to connect the side and floor doors, and a second toggle mechanism arranged to connect the side door and operating shaft. 95

15. In a car, the combination with a frame and doors, of tubular brackets fixed to the frame, an operating shaft passing through said tubular brackets, and complementary members fixed to the doors encircling portions of said brackets and forming therewith door hinges. 100

In testimony whereof, I have hereunto set my hand, in presence of two witnesses.
